UNITED STATES PATENT OFFICE.

WESLEY L. WADSWORTH, OF BROOKLYN, NEW YORK, ASSIGNOR TO WADSWORTH MOUNTING CO. INC., OF NEW YORK, N. Y., A CORPORATION OF DELAWARE.

FOLDING SCREEN.

Application filed November 2, 1923. Serial No. 672,276.

My invention relates to folding screens of the knock down type such as are used for advertising displays in store windows. These screens usually consist of a sheet of muslin on which the advertising matter appears and frame members for holding the muslin in stretched condition, the frame being made in sections so that the muslin or screen proper forms a hinge connection between the frame sections to permit the sections to be placed at different angles in order that the screen may be self-supporting. My present invention relates to a very simple and inexpensive form of knock down frame for screens of this character. The frame consists of strips disposed along the edges of the screen sections and held in spaced relation by a spreading member or arm which is attached to one of the frame members and adapted to engage another frame member to hold them spaced apart. Under the present invention this spreading member is hingedly attached to one of the frame members by very inexpensive means so that the cost of the screen is reduced to a minimum, which is an important item because these screens are generally made in great quantities and are generally used for a limited time for display purposes and are then discarded.

In the drawing forming part of this application,

Figure 1 is a rear elevation of a screen embodying my invention,

Figure 2 is an edge view thereof,

Figure 3 is an enlarged sectional view taken on the line 3—3 of Figure 1,

Figure 4 is a similar view taken on the line 4—4 of Figure 3, and

Figure 5 is a perspective view of the sheet forming the hinge for the spreader.

In Figure 1 of the drawing I have shown a screen composed of three hinged sections, 1, 2, and 3 formed with one sheet of fabric 4 as the continuous member of the screen.

All sections are alike so that a description of the parts comprising one section will answer for all of them. It will be understood that the screens may consist of only one section or any greater number of sections,

In Figure 1 I have shown the spreading member in the several sections in different positions.

Each section of the screen is shown provided with a strip 5 along one of its edges and a similar strip 6 along its opposite edge

these two strips being preferably arranged parallel to each other and I prefer to form these strips of wood. The fabric 4 of the screen may be attached to one side or surface of each frame member 5, 6 preferably by gluing it. The strips 5, 6 each have a longitudinal groove 7 projecting inwardly from one edge and these are arranged so that the grooves of the strips 5, 6 are directed toward each other. To each frame member 5 there is pivoted a spreading member 8 having one end hinged to the member 5 and having its end projecting into the groove 7 of this member. The other end of the spreader 8 is adapted to be moved into the groove 7 of the member 6 so that when the spreader is positioned at right angles to the members 5, 6 as shown in the upper section of Figure 1 the ends of the spreader will lie in the grooves 7 of the members 5, 6 and will serve to hold these latter members 5, 6 apart with the fabric between them held taut and smooth. I am not the first to employ a spreading member between parallel frame members of a folding screen but I believe I am the first to use the novel form of connection herein set forth.

In attaching the spreader 8 to the frame member 5 to form a hinged connection, I proceed as follows:

A strip 9 of pliable material such as tough paper or fabric is placed across the grooved edge of the member 5 the strip being folded upon itself and preferably cut to conform to the shape shown in Figure 5. The surface 10 of the section 11 is provided with glue or other adhesive where this section touches the member 5; and the surface 12 of the section 13 is likewise provided with glue or other adhesive. This strip is placed across the grooved edge of the member 5 and the end of the spreader member 8 is pressed against the strip 9 while the spreader is disposed in the position shown in the lower section of Figure 1; and the spreader is pressed into the groove 7. The pressure of the spreader within the groove 7 causes the strip 9 to be formed into the shape shown in the drawing. That is to say, the spreader forces the section 11 into the groove 7 so that the adhesive coated surface of this section is pressed into contact with the three surfaces of the groove. As shown in Figure 3 the section 11 has a vertical wall 14 adhering to one surface of the groove, a wall 15 adhering to

to the opposite surface of the groove, and a wall 16 adhering to the bottom surface of the groove; and the edges projecting beyond the groove are turned over as shown at 17 in Figure 3 to adhere to the edge of the member 5. While the strip 9 may be previously shaped in the manner described I prefer to shape it by the cooperative pressure between the spreader 8 and the member 5. When the 10 spreader member is placed against the strip 9 it contacts with the adhesive covered surface 12 and as the spreader is forced into the groove 7 the section 13 is formed into the shape shown in Figure 5 so that the wall 15 20 adheres to one edge of the spreader and the walls 18, 19 adhere to the opposite sides of the spreader. When the spreader has been forced into the groove the pressure between the parts holds the strip 9 snugly 25 against the several surfaces so that when the adhesive dries the strip will be firmly glued to the member 5 and the spreader 8. In the operation of forming this hinge the operator only has to position the strip 9 and press 30 the spreader 8 into the groove 7 and the screen is then ready to be rolled up and shipped. The only cost of the connection is that of the strip 9. There will be a spreading member with this form of hinge connection 35 for each section of the screen the fabric of the screen serving as a hinge connection between the adjacent frame members 5 and 6.

When the screen is to be set up for display purposes the free end of each spreader is 35 swung downwardly from the member 5, the strip 9 serving as a hinge connection be-

tween the member 5 and one end of the spreader, the latter remaining within the groove 7 of the member 5. As the spreader is swung at right angles to the member 5 the 40 free end 21 is moved into the groove of the member 6 and one section of the screen is then assembled for display and this operation is performed on each of the several sections of the screen. It will be apparent that 45 with this form of connection I avoid the expensive operation of having to place a hinge pin through the member 5 in the spreader and I avoid breakage of these strips; and the spreaders may be attached to the members 5 at any stage in the making of the screen.

Having described my invention, what I claim is:

A collapsible screen comprising a sheet of 55 pliable material and a collapsible frame therefor, including strips attached to the sheet and spaced in parallel relation, said strips having longitudinal grooves in their opposing edges, a spreader adapted to lie 60 partially in the groove of one of said strips and having one end hinged in said groove by means of a pliable member having connected sections, one of said sections being glued to the bottom and side surfaces of the 65 groove of one of said strips, and the other section having walls glued to the edge and side surfaces of said spreader.

Signed at the city, county and State of New York this 9th day of October, 1923.

WESLEY L. WADSWORTH.
